L. B. CASE

COATING MACHINE

Filed Feb. 10, 1926

UNITED STATES PATENT OFFICE.

LYNN B. CASE, OF NEW BRUNSWICK, NEW JERSEY, ASSIGNOR TO JOHN WALDRON CORPORATION, OF NEW BRUNSWICK, NEW JERSEY, A CORPORATION OF NEW JERSEY.

COATING MACHINE.

Application filed February 10, 1926. Serial No. 87,392.

My invention relates to coating machines, and particularly to that class of machine used in coating book papers, wall papers and some classes of fabric.

5 The present method of coating these materials is to apply the coating preparation to the surfaces thereof by means of immersing, spraying, or by aid of a rotary medium and immediately after applying the coating to 10 the material, it moves into contact with a series of rotary or vibrating brushes, for the purpose of laying the coating and finishing the coated surface. The number of brushes and the quality of the coating preparation 15 used has a decided bearing upon the quality of the finish of the material.

The principal object of my invention is to eliminate the rotary or vibrating brushes, and immediately after the material leaves the 20 coating head of the machine I provide smooth face rolls for the purpose of distributing the coating preparation over the surface of the material being coated, and to produce an ironing effect upon the coated surface of the material, for the purpose of producing a high 25 grade finish thereon.

Other advantages and details of the invention will be more fully disclosed hereinafter and as illustrated in the accompanying drawings, in which:

Fig. 1 is a side elevation of my improved coating machine showing a web of material passing therethrough to receive a coating on both of its sides, and

35 Fig. 2 is a fragmentary side elevation showing a web of material passing therethrough to receive a coating on but one of its sides.

Referring to Fig. 1, a side frame of the machine is illustrated at 1, it being understood 40 that such frame is duplicated at the opposite side of the machine, and 2 illustrates a supporting frame located at the receiving end of the coating machine, being provided with bearings 3 for the reception of a spindle 4 on 45 which is mounted a roll 5, of the material to be coated.

The material passes from the roll 5 in the 50 form of a web *a*, passing over a roll 6 journaled in a bearing 7 forming a portion of vertical extensions 8 of the frame 2. A roll 9 is rotatably mounted in a forked bearing 10 in the upper end of the extension 8, and is adapted to bear upon the web *a* as it passes over the roll 6.

An angularly disposed table 11 is provided 55 adjacent the delivery side of the roll 6, and is supported by arms 12 projecting from the frame 2. As the material passes from the roll 6 and over the table 11, it is engaged by a festooning apron 13 adapted to move in a 60 direction whereby the material is carried toward the frame 1 of the coating machine.

The apron 13 passes around a roll 14 rotatably mounted in bearings 15 secured to the frame 2. The opposite end of the apron 13 65 passes around a roll 16 mounted in bearings 17, adjustable within brackets 18 secured to the receiving end of the frame of the coating machine. The festooning apron may be driven from any suitable source of power, and 70 at any speed desired with respect to the roll 6 to form festoons of the desired proportions.

The web *a*, upon leaving the festooning apron 13, passes in a substantially vertical direction around a roll 19 rotatably mounted on 75 the frame 1, and between rolls 20, 21, 22 and 23 whose position may be varied with respect to the vertical plane of travel of the web *a* for the purpose of applying tension thereon, and from the roll 23 the web passes over 80 a roll 26 rotatably mounted on the frame 1.

As shown in Fig. 1, the material is to receive a coating on both sides, and for this purpose spray nozzles 30 and 31 are positioned at either side of the line of travel of the 85 web *a*, the web passing from the roll 26 between feed rolls 32 and 33 rotatably mounted in bearings 34 and 35 respectively, said bearings being vertically adjustable within the frame 1. The rolls 32 and 33 co-operate to 90 distribute the coating preparation evenly over the surface of the material.

The spray nozzles 30 and 31 are suitably connected by piping 36 to a pump 37 which in turn is connected by a pipe 38 to the bottom 95 of a tank 39 adapted to contain the coating preparation and to receive the surplus thereof as the web *a* passes between the rolls 32 and 33, the tank 39 being open at the top for such purpose.

100 As the web *a* leaves the coating head of the machine, passing between the rolls 32 and 33, it is engaged in the present instance on the bottom surface by a smooth face roll 40, positioned immediately adjacent the delivery 105 side of the rolls 32 and 33. The web *a* is next engaged by a smooth face roll 41 upon its upper surface and thereafter successively by

rolls 42, 43, 44, 45, 46 and 47 alternately engaging the web *a* on its upper and lower surfaces.

Each of the rolls 40 to 47 are provided with a shaft 48 journalled in a bearing bracket 49 slidably mounted on a pillar 50, forming part of the frame 1 of the machine. The bearing bracket 49 in each instance is provided with an extension 51 on which is mounted a motor 52 of the reversible variable speed type, and the armature shaft of each of said motors is provided with a pulley 53 adapted to receive a belt 54 which passes around a pulley 55 secured to the shaft 48 of each of said rolls. The bracket 49 is also provided with an extending lug 56 having a threaded aperture into which extends a jack-screw 57 rotatably mounted at 58 in the frame 1 of the machine.

It will be understood that the bracket 49, pillar 50 and the jack-screw 57 in each instance are duplicated at the opposite side of the machine and in order to turn both of the jack-screws 57 simultaneously, and thereby raise and lower and maintain the respective roll in a substantially horizontal plane, each of the screws 57 is provided at its lower end with a worm wheel 59, which meshes with a worm 60 secured to a transverse shaft 61 rotatably mounted in bearings secured to the frame 1. At one end of the shaft 61 is provided a hand wheel 62 by means of which the shaft may be rotated.

The rolls 40—47 are adapted to be adjusted in a vertical plane, in order that the web *a* may approach these rolls at different angles, whereby the relative surface engagement between the web *a* and the respective roll may be varied. By rotating the roll, through the medium of the motor 52, an ironing effect is produced on the coated surface of the web to lay the coating, and provide the desired degree of finish to surface of the web.

As shown in Fig. 1, the web *a* is adapted to receive a coating on both sides from the spray nozzles 30 and 31, and in this particular instance the rolls 40—47 are rotated in a counter-direction to that of the movement of the web *a*. In this manner the ironing effect above mentioned is successfully obtained.

As shown in Fig. 2, the web *a* is adapted to receive a coating on but one of its faces, the web being led over the roll 26 and under a roll 26^a rotatably mounted in bearings secured to the frames 1, 1, adjacent the roll 33 and at a point substantially below the center of rotation of said roll. In this manner the web *a* is carried below the spray nozzle 31, and thereby receives a coating on but one of its surfaces, it being understood that the flow of coating material is closed off from the spray nozzle 30 by any suitable means. In this case, where the web *a* receives a coating on but one of its sides the rolls 40, 42, 44 and 46 are driven in a direction consist-

ent with that of the travel of the web *a*, while the rolls 41, 43, 45 and 47 are driven in the counter-direction thereto, for the purpose of producing the ironing effect upon the coated surface and providing a support for the web adjacent its uncoated surface.

In each instance, after the web leaves the roll 47 it is engaged by a brush 65 on its upper surface and a brush 66 on its lower surface. These brushes are adapted to give a final finish to the coated surface before it is discharged from the coating machine. Each of the brushes 65 and 66 is secured to a transverse bar 67, mounted at each of its ends in a slidably bearing 68, adapted to a guideway 69 secured to the frame 1. The bar 67, with its respective brush, may be adjusted vertically by means of a screw 70, passing through a lug 71 on the guideway 69 and being rotatably mounted in the bearing 68, whereby, upon rotation of the screw 70 the bearing 68 secured thereto may be moved relative to the guideway 69, and the pressure of the brush upon the surface of the web *a* varied to any desired extent.

As the web *a* passes from the brushes 65 and 66 it is engaged on its lower side by a felt roll 75. The roll 75 is mounted in a manner similar to the rolls 40—47 in an adjustable bearing 76 provided with a bracket supporting a motor 77, by means of which the felt roll 75 may be rotated.

The bearing 76 is provided with a second bracket 78 adapted to support a water pan 79 into which the lower side of the roll 75 projects. As the roll 75 is rotated within the pan 79 a certain amount of water is carried by the roll 75, upward, against the lower surface of the web *a* for the purpose of moistening the web, in order that it may be more efficiently handled by the succeeding machinery to which it passes from the coating machine.

In order to control the amount of moisture carried by the roll 75 to the web *a*, I provide a scraper board or "wood doctor" 80 adjustably mounted on the pan 79 in such a manner that the pressure of the wood doctor 80 upon the surface of the roll 75 may be minutely controlled. For this purpose the wood doctor is provided with end bearings 81 adapted to receive a threaded end 82 of the shaft 83 having at its opposite end a hand wheel 84, by which said shaft may be rotated. The threaded end of the shaft is rotatably mounted in bearings 85, 85 formed on a bracket 86 secured to the pan 79.

The roll 75 and pan 79 may be adjusted vertically by means of a jack-screw 87 at each side of the machine in a manner similar to the rolls 40—47 for the purpose of controlling the relative surface engagement between the roll 75 and the web *a*.

The brushes 65 and 66, as shown in Fig. 1, are of a substantially stationary type.

I claim:

1. In a machine for coating web material, the combination of a coating head comprising a spray nozzle for applying a coating preparation to the surface of the material; means for distributing the coating preparation evenly over the surface of the material comprising a pair of cooperating rolls between which the material passes; means for applying a finish to the coated surface of the material, comprising a series of smooth face rolls adapted to be rotated in engagement with the surface of the material, some of said rolls being rotated in a manner to produce relative movement between the faces of these rolls and the surface of the material.
2. In a machine for coating web material, the combination of a coating head comprising a spray nozzle for applying a coating preparation to the surface of the material; means for distributing the coating preparation evenly over the surface of the material comprising a pair of cooperating rolls between which the material passes; and means for applying a finish to the coated surface of the material, comprising smooth face rolls adapted to rotate in engagement with the coated surface of the material, in a counter-direction to that of the travel of said material.
3. In a machine for coating web material, the combination of a coating head comprising a spray nozzle for applying a coating preparation to the surface of the material; means for distributing the coating preparation evenly over the surface of the material comprising a pair of cooperating rolls between which the material passes; means for applying a finish to the coated surface of the material, comprising a series of smooth face rolls adapted to rotate in engagement with the coated surface of the material, in a counter-direction to the travel thereof; and a second series of smooth face rolls adapted to rotate in engagement with the uncoated surface of the material and in a direction consistent with the direction of travel of said material.
4. In a machine for coating web material, the combination of a coating head comprising a spray nozzle for applying a coating preparation to the surface of the material; means for distributing the coating preparation evenly over the surface of the material comprising a pair of cooperating rolls between which the material passes; means for applying a finish to the coated surface of the material, comprising smooth face rolls adapted to rotate in engagement with the coated surface of the material, in a counter-direction to the travel thereof; and means for controlling the relative amount of surface engagement between the rolls and the material.
5. In a machine for coating web material,
- the combination of a coating head comprising a spray nozzle for applying a coating preparation to the surface of the material; means for distributing the coating preparation evenly over the surface of the material comprising a pair of cooperating rolls between which the material passes; means for applying a finish to the coated surface of the material, comprising smooth face rolls adapted to be rotated in engagement with the surface of the material; and stationary brushing means adapted to engage the surface of the material, as it passes through the machine for completing the finishing operation.
6. In a machine for coating web material, the combination of a coating head comprising a spray nozzle for applying a wet coating preparation to the surface of said material; means for distributing the coating preparation evenly over the surface of the material comprising a pair of cooperating rolls between which the material passes; and means for applying a finish to the coated surface of the material, comprising smooth face rolls adapted to rotate in engagement with the coated surface of the material; and means for moistening the web material as it is discharged from the machine to prevent checking of the finished surface as the material dries, and means for controlling the amount of surface engagement of the material with the moistening means.
7. In a machine for coating web material, the combination of a coating head comprising a spray nozzle for applying a coating preparation to the surface of said material; means for distributing the coating preparation evenly over the surface of the material comprising a pair of cooperating rolls between which the material passes; means for applying a finish to the coated surface of the material comprising smooth face rolls adapted to rotate in engagement with the coated surface of the material; and means for adjusting the rolls, individually, with respect to each other, whereby the amount of relative surface engagement between the rolls and the material may be minutely controlled.
8. In a machine for coating web material, the combination of a coating head comprising a spray nozzle for applying a coating preparation to the surface of the material; means for distributing the coating preparation evenly over the surface of the material comprising a pair of cooperating rolls between which the material passes; means for applying a finish to the coated surface of the material, comprising a series of smooth face rolls adapted to rotate in engagement with the coated surface of the material, in a counter-direction to the travel thereof; a second series of smooth face rolls adapted to rotate in engagement with the uncoated surface of the material.

rial and consistent with the direction of travel of said material; and means for adjusting the rolls of each series with respect to the other of said series, whereby the amount of 5 relative surface engagement between the first of said series and the material may be minutely controlled.

9. In a machine for coating web material, the combination of a coating head comprising 10 a spray nozzle for applying a wet coating preparation to the surface of the material; means for distributing the coating preparation evenly over the surface of the material comprising a pair of cooperating rolls between 15 which the material passes; means for applying a finish to the coated surface of the material, comprising smooth face rolls adapted to be rotated in engagement with the surface of the material; means for brushing the coated 20 surface of the material to complete the finishing operation; and means for moistening the web material as it is discharged from the coating machine to prevent checking of the finished surface as the material dries, and means 25 for controlling the amount of surface engagement of the material with the moistening means.

10. In a machine for coating web material, the combination of means for supporting a 30 roll of uncoated web material; feed rolls for removing the material from said roll; means for forming the withdrawn material into festoons to relieve the web of roll tension as it passes to the coating machine; a coating head 35 for applying a coating preparation to the surface of the material; rolls for distributing the coating preparation evenly over the surface of the material and whereby the material is withdrawn from the festoons and through the 40 coating head; adjustable retarding rolls for applying a definite tension to the material in the coating head; finishing rolls adapted to engage the coated surface; and means for rotating said rolls in a counter-direction to the 45 travel of the material, for producing an ironing effect upon said coated surface.

11. In a machine for coating web material, the combination of a coating head for applying a coating preparation to the surface of the 50 material; means for distributing the coating

preparation evenly over the surface of the material; means for applying a finish to the coated surface of the material, comprising smooth face rolls adapted to be rotated in engagement with the surface of the material; stationary brushes adapted to engage the surface of the material as it passes through the machine to complete the finishing operation; and means for adjusting the brushes with respect to the surface of the material, whereby the pressure exerted by the brushes on the material may be minutely controlled. 55

12. In a machine for coating web material, the combination of a coating head for applying a wet coating preparation to the surface 60 of the material; means for distributing the coating preparation evenly over the surface of the material; means for applying a finish to the coated surface of the material, comprising smooth face rolls adapted to rotate in engagement with the coated surface of the material; and moistening means for and to prevent the checking of the finished surface of the material located at the discharge end of the machine, comprising a felt roll engaging the material, a pan for the moistening medium, a wood doctor engaging the felt roll means for adjusting the wood doctor with respect to the felt roll, and means for adjusting the felt roll with respect to the surface of the material. 65

13. In a machine for coating web material, the combination of a supporting frame at each side of the machine; a coating head comprising a spray nozzle; means for distributing coating preparation evenly over the surface 85 of the material comprising a pair of cooperating rolls between which the material passes; means for applying a finish to the coated surface of the material, comprising a series of smooth face rolls adapted to rotate in engagement with the coated surface of the material; means on each side of the machine for moving the respective ends of the roll perpendicular to the normal plane of the material, to change the amount of surface contact between 90 each roll and the material; and means for simultaneously operating the roll adjusting means at each end of the roll. 95

LYNN B. CASE.
